(57) **CLAIM**

The ornamental design for an electrical connector, as shown and described.

DESCRIPTION

FIG. 1 is a top, front, right-side perspective view of an electrical connector according to our new design;

FIG. 2 is a top, rear, right-side perspective view thereof;

FIG. 3 is a right-side elevation view thereof;

FIG. 4 is a left-side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is an enlarged view of area 9 as depicted in FIG. 1;

FIG. 10 is an enlarged view of area 10 as depicted in FIG. 2; and,

FIG. 11 is an enlarged view of area 11 as depicted in FIG. 7.

The lighter weight dot-dash broken lines represent boundaries of the claimed design and form no part of the claimed design. The heavier weight dot-dash broken lines, which identify the portions of FIGS. 1, 2 and 7 that are enlarged in FIGS. 9, 10 and 11, form no part of the claimed design. The dash-dot broken lines depict portions of the electrical connector that form no part of the claimed design.
